UNITED STATES PATENT OFFICE

1,978,770

HAT AND COAT HANGER

Adelbert Brewer Stewart, La Mesa, Calif.

Original application May 16, 1933, Serial No. 671,415. Divided and this application November 13, 1933, Serial No. 697,846

2 Claims. (Cl. 211—33)

The present invention relates to improvements in hat and coat hangers and is a division of my co-pending similarly entitled application, Serial No. 671,415, filed May 16, 1933, now Patent No.

5 1,939,027, which issued December 12, 1933.

In common with the objects stated in the parent case, the present invention aims to provide an improved hat and coat hanger in which adequate provision is made for the neat and convenient hanging of coats, vests, hats and other garments and in which simplicity of construction and inexpensiveness in manufacture prevail.

Another object of the invention is to provide a 15 novel form of hat and coat hanger strongly made from inexpensive wire twisted and fashioned in a way to provide strength and easy reception for the garments placed thereon.

With the foregoing and other objects in view, 20 the invention will be more fully described hereinafter, and will be more particularly pointed out in the claims appended hereto.

In the drawing, wherein like symbols refer to like or corresponding parts throughout the several views,

Figure 1 is a side elevation of an improved hat and coat hanger constructed in accordance with the present invention.

Figure 2 is a front view of the same.

Figure 3 is a rear view, and

Figure 4 is a top plan view of the hat support with the remainder of the device removed.

Referring more particularly to the drawing, it will be apparent that the device is made entirely 35 of wire.

The ends of the wire are represented at 35 and 36, the same being coiled about the two standards 37 and 38 which are preferably arranged in parallelism and in contact.

40 The hat rest is formed by relatively large loops 39 and 40 formed at the upper ends of the standards 37 and 38 by carrying the wire from such standards horizontally and after the formation of the loops the terminal ends 35 and 36 of the wire are wrapped in opposite directions about the standards 37 and 38 just below said loops 39 and 40.

The standards are bent, as indicated at 41, in order that the hat rest may be carried outwardly of the wall 42. At the lower ends of the standards, such standards diverge in opposite directions, as indicated by the strands 43 and 44, which are looped, as at 45 and 46, at their outer ends in order to provide openings for screws

55 or other fastenings which will take into the wall 42. From the loop 45 a strand 47 is brought substantially horizontally in parallelism with the companion strand 43 and from this strand 47 the wire is carried outwardly from the wall to form

in the formation of this hook 48, and the other end of the wire after forming the hook 48 being carried downwardly to constitute a leg 49 which carries the other hook 50.

This hook 50 is also formed by doubling the 65 wire upon itself and thence carrying the wire upwardly in a leg 51 which parallels the leg 49. A cross wire 52 at the upper end of the leg 51 joins with the loop 46 and is crimped or bent about the leg 49 as indicated at 53.

Hats may be placed on the loops 39 and 40 forming the hat rest, and coats, vests and the like hung about the hooks 48 and 50.

This also forms an extremely cheap yet strong and rigid construction made entirely from a single strand of wire.

It will be obvious that various changes could be made in the construction, combination and arrangement of parts which could be used without departing from the spirit of my invention and I 80 do not mean to limit the invention to such details except as particularly pointed out in the claims appended hereto.

Having thus described my invention, what I claim and desire to secure by Letters Patent of 85 the United States is:—

1. In a device of the kind described, a single strand of wire fashioned to provide substantially vertical parallel standards having horizontally looped portions at their upper ends to form a 90 hat rest and with the terminal ends of the wire wrapped around the standards, the lower ends of said standards being offset to space the hat rest from a wall and said offset portion being bent in opposite directions to provide eyes for receiving 95 fastening means adapted to enter a support, and hooks formed from the lower portions of said standards and eyes.

2. In a device of the kind described, a single strand of wire bent to provide substantially vertical standards, the end portions of the wire at the upper ends of said standards being bent horizontally in opposite directions to form two opposed loops constituting a hat rest, the terminal ends of the wire being wrapped about the standards below the loops, the lower portions of said standards being offset to space the hat rest from a wall and shaped to provide eyes for resting against the wall to receive fastening means, hooks fashioned from the lower portions of said standards, one hook having legs to support the same, one of said legs crossing the other and having a crimped part.

ADELBERT BREWER STEWART.
